HANGER

Robert Phillips, Roslyn, and Bernard B. Levine, New York, N.Y., assignors to Bernard Plastics Molding Corp., Brooklyn, N.Y., a corporation of New York

Filed June 30, 1965, Ser. No. 85,966

Term of patent 14 years

(Cl. D80—8)

FIG. 4. FIG. 5.

FIG. 1 is a front perspective view of a hanger embodying our new design.

FIG. 2 is a rear elevational view thereof, a portion being broken away for convenience of illustration.

FIG. 3 is a top plan view thereof.

FIG. 4 is an elevational view taken from the right side thereof.

FIG. 5 is an elevational view taken from the left side thereof.

We claim:

The ornamental design for a hanger, as shown and described.
